UNITED STATES PATENT OFFICE.

ORIN BENNETT, OF SAN FRANCISCO, CALIFORNIA, ASSIGNOR OF ONE-FOURTH TO PETER FREDETTE AND ONE-FOURTH TO HUBERT MCL. ARMISTEAD, BOTH OF SAN FRANCISCO, CALIFORNIA.

ANNUNCIATOR.

Application filed December 22, 1922, Serial No. 608,503. Renewed November 21, 1925.

The present invention is an improved annunciator and relates to electrically operated devices for displaying at predetermined intervals of time announcements as, for instance, names or numbers of streets as the same are approached by a moving car.

5 The objects of this invention include:

(1) The provision of a device of the character described which may be installed with- 10 in a street car, occupying very little space therein, and which will automatically operate to display in proper sequence and time the names of several streets or stations as the same are approached.

15 (2) Means whereby the successive announcements will be displayed in reverse order automatically (or manually at any desired point on the trip) for the return trip of the car.

20 (3) The provision of means associated with the trolley wires of a street car system whereby trip members will lie in the path of travel of a trolley and serve to periodically close contact members and thus actuate the said annunciator within the car.

25 Other objects and advantages will appear as this description proceeds. In the accompanying three sheets of drawings,

30 Figure 1 is a front elevation of my annunciator, a portion of the face plate of the container being broken away,

35 Fig. 2 is an end elevation of Fig. 1, the end wall of the container being shown as broken away,

35 Fig. 3 is a section of Fig. 1, taken on the line III—III,

40 Fig. 4 is a view similar to Fig. 3 showing the parts therein in different relative positions for reverse operation,

45 Fig. 5 is a section of Fig. 1, taken on the line V—V,

Fig. 6 is a perspective view of a detail,

Fig. 7 is a perspective view of another detail,

45 Fig. 8 is a fragmentary view of a trolley arm showing a trip contact means associated therewith,

50 Fig. 9 is a section of Fig. 8, taken on the line IX—IX,

50 Fig. 10 is a perspective view of a roll for winding thereon a web and illustrating means whereby said web will co-operate with other parts to reverse the direction of travel thereof,

55 Fig. 11 is a diagrammatic view showing the electric wiring whereby my device is operated, and

Fig. 12 is a perspective view of the roll shown in Fig. 10, but looking from the opposite direction at the opposite end. 60

Referring to the drawings, the numeral 1 indicates a rear wall member of a housing containing working parts of my invention, and 2 a top member, 3 a bottom member, and 4 and 5 end members. 65

The rear wall member is provided with ears 6 through which are bolt holes 7 for securing the casing to a wall. The housing is closed by a face plate 8, which is removably secured thereto by tennons 9, Fig. 1, at the 70 bottom, which enter mortises or countersinks in the floor 3, and at the top by a spring clip 11.

75 The face plate 8 is provided with a window 12 through which may be sighted a portion of a web 13 to be later described. Said plate is also slotted, as shown at 14 to admit therethrough and limit the vertical movement of a lever 16 for manual extraneous control of parts within said casing. The 80 interior of the casing is divided into two compartments by a partitional wall plate 17. The major compartment thus formed is closed by the face plate 8 and the minor by a plate 18, Fig. 1, screwed to members 2, 3, 85 5, and 17.

85 The web 13 on which is recorded the data to be successively displayed through the window 12 may be of paper, or any suitable fabric, and is wound around two similar 90 rolls 19 and 21. These rolls are provided at the axes thereof with stub shafts 22, Fig. 10, which are secured against rotation with respect to said rolls.

To that stub shaft 22, on each roll, which 95 is adjacent the partition 17, I secure a ratchet wheel 23 allowing the stub shaft 22 to extend beyond the ratchet wheel, as shown in Fig. 10, for the purpose of inserting same in a hole or bearing in the wall 17. 100

The stub shafts at the ends of the rolls 19 and 21 which are remote from the ratchet wheels 23 are journalled in split bearings 24, Fig. 1, secured to the end walls of the housing. By this means, the rolls 19 and 21 with 105 the web 13 may be removed from the housing and others substituted therefor without disturbing other parts.

It will be noted that the ratchet wheels 23 are in reverse relation to each other (Figs. 3 and 4). I will now describe means both automatic and manual, whereby the 5 rolls 19 and 21 may be moved step by step to display sections of web 13 through the window 12, and for reversing the order of said display.

In Fig. 2, at 26, I show a shaft journalled 10 at its ends in the walls 5 and 17. Oscillatively mounted on said shaft is one end of a solenoid 27. The movable core of this solenoid is pivotally connected at 28 to an arm 29, secured to a rocker shaft 31 the ends of 15 which are journalled in the wall plates 5 and 17.

Secured, as by a set screw 32, on rocker shaft 31 is a rocker arm 33, from the opposite ends of which extend pivot pins 34 20 and 36. These pins extend through arcuate slots 37 and 38 respectively in the partic- 25 tional wall 17. The curvature of these slots is concentric with the rocker shaft 31. The pivot pins 34 and 36 carry respectively pawls 39 and 41 which coact at times with the ratchet wheels 23 to move the web 13. These pawls extend in opposite directions from the vertical center line of the ratchet 30 wheels 23, and as said wheels are in reverse relation to each other, it will be seen that, if one pawl be engaged with a ratchet wheel and actuated by rocker arm 33, the web 13 will wind onto one roll and unwind from the other, and if said pawl be disengaged 35 and the other engaged with its correspond- ing ratchet wheel, the movement of the rolls and web thereon will be reversed. I will now describe means whereby said pawls may be caused to selectively engage one of said 40 ratchet wheels and disengage the other.

In Fig. 4, I show the pawl 39 in engaging position and parts which co-act to disengage said pawl and engage pawl 41 as shown in 45 Fig. 3. The manually operated means for reversing the direction of travel of web 13 is controlled by the lever 16 which is pivoted at one end on a screw 42, threaded into and extending outwardly from the wall 17. In Fig. 7 I show the lever 16 in perspective. 50 At 40 I show a drill hole for engaging the screw 42. At 43 I show a screw which pivotally secures to lever 16 one end of a link member 44, Figs. 3 and 4, the opposite end 55 of which is provided with a slot 46 for sliding engagement with a pin 47 protruding from the pawl 39. As the pin 47 is between the pivot of pawl 39 and that portion thereof which engages the ratchet wheel, an upward thrust of lever 16 will raise the said 60 pawl out of engagement with said wheel.

Said pawl 41 is provided with a finger 45, Fig. 3, extending from the pivotal point of said pawl in the opposite direction. This finger 45 bears against the lever 16 and, 65 when depressed thereby, raises said pawl 41

out of engagement with the ratchet wheel. As lever 16 is raised the pawl 41, assisted by a counterweight 46, gradually descends to operative position.

In order to yieldably maintain the pawls 70 in either operative or inoperative positions and to provide means automatically co-operative with the web 13 for reversing the position of said pawls, I provide a lever 46, shown in perspective in Fig. 6. 75

This lever 46 is drilled, as shown at 47, for pivotal engagement thereof by the screw 42. The lever 46 is provided with a stud 48 which is at all times slidably engaged with the bifurcated end of a lever 49, Fig. 4, 80 pivoted on a stub shaft 51. The levers 46 and 49 are yieldably maintained in different relative angular positions by a tension spring 52 secured at one end to a pin 53 on lever 46 and at the opposite end to a pin 54 on 85 lever 49.

The lever 46 is pivoted at the same point as is the lever 16 and in order to provide for a movement of lever 46, relative to lever 16, and to limit said movement, I provide a slot 90 56 in lever 46, Fig. 6. The screw 43 extends through said slot 56 and acts as a stop at each end of said slot.

It will be seen from this description, so far, that, when lever 16 is in the position 95 shown in Fig. 3, continuous reciprocation of rocker arm 29 by solenoid 27 will cause pawl 41 to advance, step by step, the roll 21, moving web 13 downwardly past the window 12, and that, when said lever 16 is in the position shown in Fig. 4, the said reciprocation of rocker arm 29 will cause pawl 39 to move, step by step, the roll 19, moving the web 13 upwardly past the window 12. 100

If the lever 16 be held in an intermediate 105 position neither pawl will engage and the rolls 19 and 21 may be removed from the housing without disturbing any of the mechanism.

In order to cause automatic reversal of 110 the direction of travel of the web 13 as each end of the web is reached in unwinding, I provide the following details: In Fig. 10 I show one of the rolls 19 and 21 in perspective and in Fig. 12 I show a respective view 115 of the opposite end of said roll. At 57 I show a flat bar held in a groove in the periphery of the roll and bent toward the axes of the roll at the ends thereof. At 58 on each end of the roll I show screws which 120 serve as pivots for a frame composed of end members 59 and 61 and parallel transverse bars 62 and 63.

The frame so formed is so constructed that it normally lies flush with the periphery of 125 the roll to which it is pivoted but may be swung on its pivots to the position shown in Fig. 5, by the pull of the web 13. The web is secured at each end by being passed under the bar 57 before said bar is screwed 130

in place in its groove. The web is also passed between the parallel bars 62-63 as shown in Figs. 5 and 12.

It will be seen that, while one of the rolls 5 carries several layers of the web 13, the frame will assume the position shown in the roll 19, Fig. 5, and the parallel bars 62-63 will seat in a groove 64, but, when the end of the roll is reached in unwinding, the pull 10 from the full roll (exerted in a direction tangential to the periphery of the empty one) will cause the web 13 to unseat bars 62-63 from groove 64 and swing the frame on its pivots to the position shown on roll 15 21, Fig. 5. To make use of this movement to reverse the direction of travel of web 13 automatically, I provide a pin 66, Figs. 1 and 10, extending from the frame members 59. This pin co-acts with fingers 67 on lever 20 46 to reverse the position of lever 16. It will be understood that each of the rolls 19-21 is provided with a frame and pin 66 and that fingers 67 extend from opposite sides of lever 46, whereby the automatic reversal 25 is accomplished when either end of web 13 is unwound.

In order to prevent spinning of the rolls 19 and 21 when actuated by the solenoid 27 I provide a brake element consisting of 30 spring clips 68, Fig. 5, pivotally secured at 69 and held by tension springs 71 to bolts 72. The tension of springs 71 may be adjusted by nuts 73 and thereby predetermine the pressure exerted by the brake elements.

35 In Fig. 11, I show diagrammatically the wiring circuit for actuating my device.

At 74 I show a battery and at 77 a wire connecting same with a contact 78. This contact is normally held out of contact with a similar contact 79 by a spring 81. When the contacts 78 and 79 are closed, current from battery 74 passes through a wire 82 to one terminal of an electromagnet 83. The purpose of the magnet 83 is to hold the current after the momentary closing of the contacts 78 and 79 during the operation of the solenoid 27, the action of which is comparatively slow.

From the other terminal of magnet 83 50 a wire 86 leads to one terminal of the solenoid 27 from the other terminal of which a wire 76 leads to the opposite pole of the battery.

At 84 I show an armature. When this 55 armature is attracted by the energized magnet 83 current (following the line of least resistance) passes from battery 74 through a wire 87 and (though contact be broken between points 78 and 79 by spring 81) the core of solenoid 27 slowly descends until contact is broken by a finger 88 secured to arm 29 which encounters and lifts armature 84 away from magnet 83.

At 89 I show a spring secured at one end 60 to a pin 91 extending from wall 17 and at

the opposite end to arm 29. When the solenoid 27 is de-energized this spring returns the core of the solenoid and arm 29 to their initial positions.

It will thus be seen that I have provided means for advancing step by step, the web 13, and means whereby said web will reverse its direction of travel automatically, when actuated by successive reciprocations of the solenoid 27. In order to provide 70 means for periodically closing the contacts 78 and 79 without attention on the part of the conductor of the car, I provide the following:

In Figs. 8 and 9 I show the conventional 80 trolley arm at 91 provided with a pintle 92 for a trolley wheel 93 grooved for travel underneath a trolley wire 94 supported at intervals throughout its length by grippers 96 which, in turn, are suspended by trans- 85 verse guy wires 97. Secured to the bifurcated end of trolley arm 91 and approximately concentric with pintle 92 is a fender block 98 of insulative material in the form of a truncated cone. This block is pro- 90 vided with a tubular boss 99 of insulative material fixed against rotation. Rotatable within said boss is sleeve 101 open at one end and closed at the end remote from block 98. 95

Threaded into the sleeve 101 is a metal pin serving as contact 78. This pin extends through a slot 102 in boss 99 and said slot limits the degree of rotation of sleeve 101 relative to boss 99. The contact pin 78 is 100 normally held in the position shown in Fig. 9 by a tension spring secured at one end to said pin and at the opposite end to block 98.

At 103 I show a pendulum weight pivotally suspended by arms 104 from guy wire 97. When, in the forward travel of trolley arm 91, the pin 78 encounters a pendulum weight 103 the said pin is forced backwardly in slot 102 until said pin encounters contact 79 (in this case secured to the block 98) 110 whereupon the circuit shown in Fig. 11 will be momentarily closed, energizing magnet 83 and solenoid 27, and advancing web 13 one step. By distributing the pendulum weights 103 at suitable intervals on the trolley wire 115 line the step by step advance of web 13 will coincide with cross streets or stations.

At 106 I show a tension spring secured at one end to armature 84 and at the opposite end to a pin 107 secured to wall 17. This 120 spring normally holds said armature suspended over magnet 83.

In order to delay the downward stroke of the core of solenoid 27 I provide an air check shown on dotted lines in Fig. 2. A ball 108 seats in a well 109 and closes a passage 110 leading to the atmosphere. This ball check delays the down stroke and does not affect the up stroke of the core.

I claim:

1. An annunciator comprising a housing, rolls journaled in said housing, a web secured at each end to one of said rolls, pawl and ratchet means for actuating said rolls to effect a step by step movement of said web to successively expose portions thereof through a window in said housing, manually operated means for selectively engaging a pawl with either of said rolls to determine the direction of travel of said web, automatic means, responsive to the movement of said web, whereby said engaged pawl will disengage and the other pawl engage when said web is unrolled to either of its ends, and means, responsive to a reciprocating movement, for actuating said pawl and ratchet means.
  2. An annunciator comprising a housing, rolls journaled in said housing, a web se-
- cured at each end to one of said rolls, pawl 20 and ratchet means for actuating said rolls to effect a step by step movement of said web to successively expose portions thereof through a window in said housing, manually operated means for selectively engaging 25 a pawl with either of said rolls to determine the direction of travel of said web, automatic means, responsive to the movement of said web, whereby said engaged pawl will disengage and the other pawl engage when 30 said web is unrolled to either of its ends, reciprocal means for actuating said pawl and ratchet means, and means yieldable to both of said manual and automatic means, for retaining either of said pawls in operative engagement with one of said rolls. 35

In testimony whereof I affix my signature.
ORIN BENNETT.
